UNITED STATES PATENT OFFICE

161,307

ACCOUNTANT'S RULER

John Bischof, Racine, Wis., assignor to Bischof Die & Engraving Co., Racine, Wis., a partnership

Application March 30, 1950, Serial No. 8,871

Term of patent 7 years

(Cl. D52—1)

To all whom it may concern:

Be it known that I, John Bischof, a citizen of the United States residing at Racine, in the county of Racine and State of Wisconsin, have invented a new, original, and ornamental Design for Accountant's Ruler, of which the following is a specification, reference being had to the accompanying drawing, forming part thereof.

I claim:

The ornamental design for an accountant's ruler, as shown.

JOHN BISCHOF.
